UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed September 10, 1924. Serial No. 736,860.

This invention relates to machines for cutting stencils, and particularly to the kind shown in the patent to Sterling Elliott, No. 1,378,771, dated May 17, 1921. In said patent, carbon is deposited on the rear of the stencil-blank by means of carbon-paper, conducted from a supply-roll, placed in a cylindrical container, said container having both ends open for the insertion and withdrawal of said roll. Said container is disposed above and behind the platen, the carbon-paper passing downwardly and around the platen and upwardly between the platen and the stencil-blank. As both ends of this container are open, the carbon-roll is liable to move laterally and slip out.

A feature of this invention is to provide means for holding the carbon-roll within its container, but permitting the ready insertion or removal of the roll.

In said patent to Elliott, a device is provided for guarding and guiding the free used portion of the carbon-sheet after it advances around the platen. Said patent also includes a finger-piece to lift the guiding means in order to release the carbon-sheet. In accordance with the present invention, the means for holding the carbon-roll within its container is supported on said finger-piece.

Other features and advantages will hereinafter appear.

In the accompanying drawings,

Figure 1 is a top plan view of a typewriter carriage and associated parts, with the present invention applied thereto in its stenciling position.

Figure 2 is a vertical section taken on a plane indicated by the line 2-2 of Figure 1, but shows the stencil-holder in its raised position.

Figure 3 is a detail perspective of the device for holding the carbon-roll within its container.

Referring to the drawings, a platen 10 is mounted on a shaft 11 which is journaled in the platen-frame 12 of the usual carriage. A hand-wheel 13 is fastened to each end of said shaft 11 for rotating the platen 10. A stencil-blank 14 is held in proper position in front of said platen 10, for receiving impressions of type 15, by means carried by the platen-frame 12 and movable therewith. As here shown, the holding means comprises a pair of stationary jaw-members 17 for

engaging the side edges of the stencil-blank 14. Said jaw-members 17 are carried by a pair of frame-bars 18 which are pivotally mounted on a shaft 19 which is positioned close to the rear paper-table 19', so that when the frame-bars 18 are thrown rearwardly to the position shown in Figure 2, the center of the weight of the frame will be close to the carriage. Said shaft 19 is mounted on projections (not shown) extending rearwardly from the typewriter carriage 16. Said frame-bars are rigidly secured together by said shaft 19 and by a yoke-member 18', thus forming a rigid structure which is arranged for movement about the pivot-rod 19. The clamping device also includes a pair of front jaw-members 20 pivotally mounted on said frame-bars 18 and arranged to engage said stencil-blank 14 and hold the same pressed against the stationary jaw-members 17 by means of springs 20' pressing against said jaw-members 17. Said jaw-members 20 are disposed above and at the front of the platen 10, so as to hold the stencil-blank 14 in a vertical position against said platen 10 for receiving impressions from type 15.

Said jaw-members 20 are mounted to be moved outwardly, said moving means shown here as a yoke 21 carried by the frame-bars 18 and loosely mounted on a rod 22. The ends of said yoke 21 terminate in lateral extensions 23 extending below said jaw-members 20 and disposed to engage the same to move them outwardly and disengage the stencil-blank 14. Said yoke 21 carries an arm 24, which arm 24 is disposed in front of an arm 25, mounted upon a cross-bar 26 arranged between the frame-members 18, so that the two arms may be grasped for rocking said yoke 21.

The stencil-blank 14, while held by the clamping device, is arranged for movement vertically step by step, and for this purpose line-spacing means is provided. Said line-spacing means includes a roll 27 journaled in an ear 28 fixed to a hub 29 mounted on a rod 30, which rod is secured at its ends to the end portions 31 of a yoke 32, which, in turn, is secured on the carriage 16. By reason of this construction, said roll 27 is movable bodily with the carriage, and is freely rotatable and serves as a support and receives upon it a cam 33 which is mounted on the frame-bars 18. Said cam 33 is made

of a varying radius, so that as it is turned the frame-bars and clamping device, supported thereby, will be raised to be held at different elevations. Said cam 33 is secured to a shaft 34, which shaft has secured to it at one end a hand-wheel 35 for rotating said cam and lifting the clamping device. The cam 33 normally rests against a pin 36 carried on one of the frame-bars 18, in which 5 position that portion thereof of shortest radius will engage the roll 27, and, when it is desired to move the stencil-blank 14 in an upward direction, the shaft 34 will be turned to rotate said cam 33. Means (not shown) 10 is provided for holding said cam 33 against the fixed pin 36.

To hold the shaft 34 against backward rotation and also in different elevated positions, a wheel 37, mounted on the shaft 34, 20 is provided. Said wheel 37 has teeth 38 formed on its periphery, which teeth 38 are arranged to be engaged by a detent 39 formed on an arm 40 which is loosely pivoted at 41 to one of the frame-bars 18. 25 Said detent-arm 40 is limited in its movement on its pivot by reason of its slotted end portion 42 engaging a pin 43 carried on the adjacent frame-bar 18. The detent 39 acts to hold the toothed wheel 37 in any 30 position desired, but permits rotation in one direction only. The teeth 38 on said wheel 37 are arranged in groups, the teeth of each group including approximately the same arc or portion of the wheel, and the teeth of 35 each group varying in length. This provides for varying the number of lines and also for spacing the lines more or less widely apart.

After the typing operation on a stencil-blank 14 is completed and it is desired to remove said blank 14, the clamping jaws 20 are released by rocking the yoke 21 and the stencil-blank 14 disengaged. At the same time the line-spacing means is adapted to be 40 operated automatically and is caused to resume its normal position. For this purpose suitable connecting means are provided between the detent-arm 40 and the clamping device, by which said arm 40 will be lifted and its detent 39 released from engagement 45 with the toothed wheel 37 by a movement of the clamping device.

To accomplish this, said detent-arm 40 has loosely connected with it one end of a link 44, the other end of which link 44 is connected with an ear 45 formed on one of the jaw members 20, so that, upon movement of said jaw-members 20, the detent-arm 40 will be correspondingly moved and the toothed wheel 37, cam 33 and cam-shaft 34 are then free to be rotated to normal position, the cam 33 again engaging the pin 36 carried on one of the frame-bars 18.

In order that the stencil-blanks 14 may receive impressions, carbon must be deposited

on the rear thereof, and, for this purpose, a strip of carbon-paper 46 is provided, which is arranged in roll-form in a cylindrical container 47, having both ends open for the convenient insertion and withdrawal of said roll of carbon-paper 46. Said carbon-strip 46 passes downwardly and around the platen 10 and upwardly over said container 47.

In order to hold said carbon-strip 46 on the platen 10, a roll 48 may be employed, 75 which is loosely mounted on a shaft 49, the ends of which shaft 49 are mounted in bearing strips 50, which are extended from a sleeve 51 carried on a shaft 52. Said roll 48 is normally pressed against the platen 10 by a spring 53, and may be swung away from the platen to release the carbon-sheet 46, by an arm or finger-piece 54. Said bearing strips 50 may be extended at the other side of said sleeve 51 and arranged to pivotally support the arm 54 which extends upwardly and has a weighted end portion 55 for guiding and guarding the free used end of said carbon-strip 46. The container 47 is fastened to the curved portion 56 of a 90 bracket 57, the lower end of which is fastened on the shaft 19 by screws 58. A projecting portion or stop 59', formed on the bracket 57, limits the backward swing of the frame 18. 95

It is a feature of the present invention to prevent the carbon-roll from moving laterally of its container 47 and slipping out of the same. To accomplish this, a cross-piece or bar 59 is rigidly mounted on the arm 54 100 by means of screws 60. Said bar 59 terminates in downwardly-extending flange-portions or ears 61. When said arm 54 is in effective position, said ears 61, carried by the bar 59, are positioned adjacent the open 105 ends of said container 47 and serve as ends therefor, holding the carbon-roll within the same. The bar 59 with its ears 61 together with the arm 54 and its weight 55 also serve to guide the movement of the free end 110 of the carbon-strip 46.

Whenever it is necessary to insert a new carbon-roll in the container 47, the clamping device and line-spacing mechanism may be swung upwardly and rearwardly on the pivot-bar 19, the stop 59' limiting said movement. The arm 54 may then be swung forwardly, by grasping the weight 55 and rocking said arm 54 around its pivotal connection with the bearing strips 50, to the position shown in dotted lines in Figure 2, whereby access may be had to the container 47, for inserting or withdrawing a carbon-roll. 115

Variations may be resorted to within the 125 scope of the invention, and portions of the improvements may be used without others.

Having thus described my invention, I claim:

1. In a machine for impressing characters 130

on stencil-blanks, the combination with the platen and the carriage of a typewriting machine, of a container having both ends open for holding a roll of carbon-paper in strip form, said carbon-strip arranged to be fed around said platen, a device for guarding and guiding the free end portion of said carbon-strip, and means carried by said device for holding said roll of carbon within said container.

2. In a machine for impressing characters on stencil-blanks, the combination with the platen and the carriage of a typewriting machine, of a container having both ends open for holding a roll of carbon-paper in strip form to be fed around the platen, a device for guarding and guiding the free used end of said carbon-strip, said device arranged to be moved into or out of effective position, and means carried by said device for holding said roll of carbon-paper within said container.

3. In a machine for impressing characters on stencil-blanks, the combination with the platen and the carriage of a typewriting machine, of a container having both ends open for holding a roll of carbon-paper in strip form, said carbon-strip arranged to be fed around said platen, a device for guarding and guiding the free used end of said carbon-strip, and means carried by said device for holding said roll of carbon-paper within said container, said means being movable into either effective or ineffective position.

4. In a machine for impressing characters on stencil-blanks, the combination with the platen and the carriage of a typewriting machine, of a container having both ends open for holding a roll of carbon-paper in strip form to be fed around said platen, a weighted arm overlying the used portion of said carbon-strip to guide and guard said used portion of said carbon-strip, and means mounted rigidly on said arm for holding said roll of carbon-paper within said container.

5. In a machine for impressing characters on stencil-blanks, the combination with the platen and the carriage of a typewriting machine, of a container having both ends open for holding a roll of carbon-paper in strip form, said carbon-strip arranged to be fed around said platen, an arm overlying the used portion of said carbon-strip to guide and guard the same, and a bar extending across said arm and mounted fixedly thereon, said bar terminating in downwardly-projecting flange portions or ears to form ends for said container to hold said carbon-rolls within said container.

6. In a typewriting machine, the combina-

tion of carriage, a platen on said carriage around which a carbon-strip may be fed from a supply-roll, a cylindrical container supported on said carriage for the supply-roll, said container having open ends to enable the supply-roll to be inserted from either end, a pivoted device to swing at right angles to the direction in which the supply-roll is inserted into the container, said device having ears to serve as ends for the container to hold the supply-roll in said container, means to hold said device in its effective position, and a holder for a stencil-blank pivoted on said carriage and swingable from a lowered, forward position to an upper, rearward position, said pivoted device being swingable when said holder is in the latter position, to move said ears from the ends of said container.

7. In a typewriting machine, the combination of a carriage, a platen on said carriage around which a strip of material may be fed from a source of supply, a container supported on said carriage for the material supply to enable the material supply to be inserted, a feed-roll to assist in feeding the material around said platen, a finger-piece to actuate said feed-roll to release said material, and a device supported on said finger-piece and effective to serve as an end for said container, to hold the material supply in said container, said finger-piece being pivotally supported to swing the end to give interior access to the container.

8. In a typewriting machine for impressing characters on stencil-blanks, the combination of a platen, a carriage therefor, an open container permitting the insertion therein and removal therefrom of a roll of carbon-paper in strip-form, a pair of ends for said container, a connecting piece between said ends, and means supporting said connecting piece for pivotal movement on said carriage to permit said ends to be simultaneously swung to and from closure position at said container.

9. In a typewriting machine for impressing characters on stencil-blanks, the combination of a platen, a carriage therefor, an open container for a roll of carbon-paper in strip-form, a pair of ends, a support for said ends mounted for pivotal movement forwardly of said container, a holder for a stencil-blank pivoted on said carriage and movable from a lower, forward, operative position to an upper, rearward position and permitting, in the latter position, the forward movement of said ends, and means for limiting the rearward movement of said support and thereby positioning said ends over the ends of said container.

JOSEPH LINDBURG.
